UNITED STATES PATENT OFFICE.

CHARLES D. FOX, OF PHILADELPHIA, PENNSYLVANIA, ASSIGNOR TO H. C. FOX & SONS, OF SAME PLACE.

MOLD FOR MANUFACTURING SEAMLESS GLASSWARE.

SPECIFICATION forming part of Letters Patent No. 242,622, dated June 7, 1881.

Application filed April 27, 1881. (No model.)

To all whom it may concern:

Be it known that I, CHARLES D. FOX, a citizen of the United States, residing at Philadelphia, in the county of Philadelphia and State of Pennsylvania, have invented certain new and useful Improvements in Molds for Manufacturing Seamless Glassware; and I do hereby declare the following to be a full, clear, and exact description of the invention, reference being had to the accompanying drawings, which form part of this specification, in which—

Figure 1 is a vertical transverse section of my improved mold. Fig. 2 is a rear elevation of the same. Figs. 3, 4, 5, and 6 are plans illustrating the different positions occupied by the movable parts of the mold when the latter is in use; and Fig. 7 is a broken elevation, partly in section, of a vessel or bottle blown in one of my improved molds.

My invention has for its object to provide a mold for the manufacture of seamless glass bottles and other vessels or articles having a wide mouth or neck, such mold being designed and adapted to permit the formation of such seamless articles without the necessity of rotating the same while being blown.

My invention consists in the peculiar construction and combination of parts hereinafter fully set forth, having reference, principally, to the following points: first, to making that part of the mold in which the neck of the vessel is blown in the form of a seamless or unbroken ring in one piece and separate from the body; second, to connecting the neck-ring, made in one seamless piece, to the body of the mold by a hinge or joint, so as to permit its being thrown up or off said body to allow the bottle or other vessel to be lifted out of the latter; third, to forming the top of the mold with an annular groove on its under side, into which the metal flows when the bottle or other article is being blown, in order to reduce the thickness of the glass above the neck, so that it may be readily chipped off without danger of fracturing the latter; fourth, to forming a glass mold with two covers or tops, one over the other, the upper top having a central hole of less diameter than the hole in the other, whereby the blow-over formed above said upper top will pass through the hole in the lower top, as and for the purpose hereinafter fully explained; and,

fifth, to certain details of construction and combination hereinafter fully set forth.

Referring to the accompanying drawings, A designates the body of a mold composed of 55 metal and formed in one piece. Such body of itself does not constitute any part of my present invention, and hence need not be further described.

B represents a metal ring, which is without 60 a seam of any character, and is in one single piece, forming an unbroken annulus, which is separate from—*i.e.*, not made integral with—the body A. The neck of the bottle or other vessel to be blown in the mold is formed in this 65 ring, which is secured to the body by a hinge, b, to permit it to be thrown back on said body, so as to allow the article formed in the mold to be lifted vertically out of the latter. The ring B is recessed on its under side, forming a 70 socket, b', which receives a boss, a, projecting upwardly from the body, and secures said ring against lateral movement when down on said body. The ring B has on its upper side a boss, b'', the outer wall or periphery of which is beveled, forming an annular dovetail, for a purpose hereinafter specified.

C and D represent two covers or tops for the mold, one fitting over the other, and each formed in two sections, c c and d d, provided 80 with separate handles c' d', and hinged at e e. The top C is recessed to receive the boss b'' of the ring B, the wall c' of said recess beveling corresponding to the periphery of said boss. Said top C has also a boss, c'', with beveled 85 periphery c', which fits in a corresponding recess, d'', in the upper top, D. The beveling of the bosses and corresponding inclination of the walls of the recesses or sockets in which they fit effects this when said tops are closed. By 90 taking hold of the handles and lifting the same the ring B will be also raised, as hereinafter set forth. It also prevents the neck-ring and tops from being lifted when the glass is being blown in the mold. The top C is formed 95 on its under side with an annular groove, f. The outer wall of this groove starts at its bottom on a line slightly within the diameter of the neck-opening B' in the ring B, so as to leave a narrow annular shoulder, f', projecting over said neck-opening. The top C has a center hole, f'', which, at its base, is of nearly 100

the same diameter as the inside diameter of the groove f . The top D has a hole, d^3 , of so much less diameter than the hole f^2 in the top C that the "blow-over" formed on said top D will pass through the hole f^2 in said top C.

The operation is as follows: The ring B being turned down and the tops C D opened, as shown in Fig. 3, the neck-opening B', which is of relatively large diameter, is exposed, permitting easy access to the body of the mold, and permitting the ready insertion therein, through said opening, of sufficient metal to form the bottle, jar, or other vessel designed to be blown in the mold. The molten metal being inserted by the blower, the tops are closed by an attendant and the article blown. As the metal by the act of blowing has entered the groove f in the top C it will prevent said top from being opened. The top D may, however, be opened, and this is done by means of the handles d' d' . As the "blow-over" formed on said top D is of less diameter than the hole f^2 in the top C it may be passed through latter. To effect this said top C is lifted by the handles c' , carrying with it the ring B, leaving the article which has been blown standing in the body of the mold, with so much of said article as includes the neck and the adhering glass over said neck projecting above said body. The article thus formed is then lifted out of the mold, a detail section thereof presenting then the appearance substantially indicated in Fig. 7. The glass above the neck is then (by a suitable appliance) chipped off and the top of said neck ground. The glass above the neck formed by the groove f , being of reduced thickness, may be readily chipped off, the shoulder f' forming on the article blown a thin portion, which will cleave readily in the line of the top of the neck under the action of the chipper without fracturing said neck.

The article blown in this mold is without seam or fin in the body, shoulder, or neck, and possesses a great advantage over such articles as heretofore made with a seam or seams in the neck. Where a mold is so constructed as to form a seam or fin on the neck the joint which produces such seam becomes, in course of usage, quite open, enlarging the seam, and thus preventing the tops (which are made uniform in size) from being slipped down over the necks. Such enlarged seams or fins will also be produced, even in new molds as heretofore constructed, if the separable sections or two-part tops which form the necks are not brought and held tightly together when the vessels are being blown in the molds. Besides, no matter how carefully such molds which make neck-seams are worked, they can never produce articles having as finished an appearance, or capable of having a top fitted therein as neatly and snugly, as those without seams, a seam, no matter how thin or light, being always a detriment to finish and tight fitting.

I have shown and described a mold designed

and adapted to form a cylindrical or round bottle or jar; but I do not limit my invention to any particular shape or configuration, as molds embodying the principles of construction herein and hereby set forth and claimed may be made to produce bottles, jars, and other vessels or articles of oval, square, oblong, or any other design.

In cases where a particularly wide-mouthed vessel is to be made the ring B and top C may be made in one piece, with the groove f , as above described. In such case the opening f^2 must be of sufficient diameter to readily permit the necessary metal to be passed through it. The operation and effect in such case will be the same as above set forth, except that the top C will not then open laterally, but will be moved only with the ring B, the top D being as already described.

What I claim as my invention is as follows:

1. A mold for bottles, jars, or other articles of glassware, having a seamless neck-ring in one piece separate from the body, substantially as shown and described.

2. The combination, with the body of a mold for bottles, jars, or other articles of glassware, of a seamless neck-ring made in one piece and hinged to said body, substantially as shown and described.

3. A mold-top for articles of glassware, having on its under side an annular groove, f , substantially as and for the purpose set forth.

4. The combination, in a mold for articles of glassware, of a neck-ring, B, and a top, C, having an annular groove of less diameter than the hole in said ring, so as to form a shoulder, f' , substantially as and for the purpose set forth.

5. The combination, with the body of a mold for articles of glassware, of two tops, C D, one above the other, the hole in the upper top being of less diameter than the hole in the other top, substantially as shown and described.

6. The combination, in a mold for articles of glassware, of a neck-ring, B, hinged to the body A, and having a boss, b , with beveled periphery, and a sectional top, C, having a recess, b^2 , with inclined walls, forming a socket for said boss, substantially as shown and described.

7. The combination, in a mold for articles of glassware, of a top, C, having boss c^3 , with beveled periphery, with superposed top D, having a corresponding recess, d^2 , substantially as shown and described.

8. The combination of mold-body A, seamless neck-ring B, and double top C D, said parts being constructed and designed for operation substantially as shown and described.

In testimony that I claim the foregoing I have hereunto set my hand this 22d day of April, 1881.

CHARLES D. FOX.
